UNITED STATES PATENT OFFICE.

JOHN B. D'HOMERGUE, OF PITTSBURG, PENNSYLVANIA, ASSIGNOR OF ONE-HALF TO JULIUS DE LONG, OF NEW YORK, N. Y.

LINING.

SPECIFICATION forming part of Letters Patent No. 665,828, dated January 8, 1901.

Application filed November 4, 1899. Serial No. 735,800. (No specimens.)

To all whom it may concern:

Be it known that I, JOHN B. D'HOMERGUE, a resident of Pittsburgh, in the county of Allegheny and State of Pennsylvania, have 5 invented a new and useful Improvement in Linings; and I do hereby declare the following to be a full, clear, and exact description thereof.

My invention relates to linings, and has 10 special reference to such linings as are used for carpets, refrigerator-cars, cold-storage houses, dwellings, buildings, &c.

One object of my invention is to provide such a form of lining which will resist heat 15 or cold as well as one which will be a perfect non-conductor of sound for floors and walls; and a further object of my invention is to provide a cheap and simple form of lining which will be easily and cheaply manufactured as 20 well as one which will be air, dirt, and dust proof when in use.

A still further object of my invention is to provide such a form of lining that will prevent the threads for securing the lining together from becoming withdrawn in case they 25 should become broken from any cause, as is the case in the ordinary linings where chain-stitching is used.

My invention consists, generally stated, in 30 the novel arrangement, combination, and construction of parts, as hereinafter more specifically set forth and described, and particularly pointed out in the claims.

To enable others skilled in the art to which 35 my invention appertains to construct and use the lining, I will describe the same more fully, referring to the accompanying drawings, in which—

Figure 1 is a top view of a portion of my 40 improved lining, showing the front, top, or one side of the same broken away at one end. Fig. 2 is a bottom view of the same, and Fig. 3 is a cross-section of the same.

Like numerals hereinafter indicate like parts in 45 each of the figures of the drawings.

As illustrated in the drawings, 1 represents the lining, which is composed of the sheathing of paper 2 or other suitable material to form one face, the bottom, or back 3, and 4 50 represents the filling material of any well-known fiber, such as cotton, hair, &c. This

filling material 4 is held or secured to the face, bottom, or back 3 by means of side edges 5 of said face, bottom, or back 3 being bent or turned over the top of said filling material 4 55 to form the side grooves 6 therein. These side edges 5 are secured to the face, bottom, or back 3 and filling material 4 by means of threads 7, which pass through the ends of the said side edges 5, filling material 4, and face, 60 bottom, or back 3 to form the chain-stitching on each side of the lining 1. Tapes or strips 8, formed of paper or other suitable material, extend along the length of the surface of the bottom or back 3 and are secured to said bottom or back 3 and filling material 4 by means of the threads 9. Tapes or strips 10, formed of paper or other suitable material, also extend along the length of the surface of the filling material 4 opposite the tapes or strips 70 8, and they are secured to said filling material 4, face, bottom, or back 3 and tapes or strips 8 by means of the said threads 9, which form the chain-stitching on each side of the lining 1. A sheathing of paper 12 or other 75 suitable material to form the opposite face, front, or top 13 of the lining 1 is secured to the same by pasting, gluing, or cementing said face, front, or top 13 with any suitable material to the tapes or strips 10 over the 80 threads 9 and to the side edges 5 over the threads 7.

In the manufacture of my improved lining the sheet of paper 2 to form the face, bottom, or back 3 is cut to the required size and the 85 required amount of fibrous filling material 4—such as cotton, hair, &c.—is placed on the same. After this is accomplished the sides of the face, bottom, or back 3 can be bent or turned over onto the filling material 4 to form 90 the side edges 5 thereon and grooves 6, and such side edges 5 secured to said face, bottom, or back 3 and filling material 4 by the threads 7, which pass through said face, bottom, or back 3, filling material 4, and through 95 the ends of the side edges 5 to form the chain-stitching on each side of the lining 1. During this operation the tapes or strips 8 and 10 are placed along the length of the face, bottom, or back 3 and along the length of the 100 surface of the filling material 4, and such tapes or strips 8 and 10 are secured to the

bottom or back 3 and filling material 4 and to each other by means of the threads 9, which pass through the face, bottom, or back 3, filling material 4, and tapes or strips 8 and 10 5 to form the chain-stitching on each side of the lining 1. The sheet of paper 12 to form the opposite face, front, or top 13 of the lining 1 having been cut to the required size can then be placed or secured to the lining 1 10 by pasting, gluing, or cementing the same to the tapes or strips 10 over the threads 9, forming the chain-stitching, and the side edges of said face, front, or top 13 can be pasted, glued, or cemented to the side edges 5 over the 15 threads 7, forming the chain-stitching, when the lining 1 is ready for use.

It will thus be seen that my improved lining is cheap and simple in its construction of parts and process of manufacture. It can 20 be easily and rapidly manufactured and is greatly strengthened by its peculiar construction. It forms a completely-covered lining on its exposed parts and presents no openings or holes caused by stitching or sections, 25 so rendering the same impervious to dirt, dust, and air, as well as a perfect non-conductor of sound.

It will further be seen that the lining forms a perfect insulator, and the threads of the 30 same forming the chain-stitching for securing the parts together will be prevented from becoming withdrawn when one of the threads is broken or fractured.

It is obvious that my improved lining can 35 be used as an insulator for many and different purposes by the use of suitable filling material for resisting heat or cold and that the same can be used for packing purposes and linings other than those previously mentioned.

If desired, my improved face or covering can be used on both sides of the lining, and various other modifications in the construction and arrangement of the lining may be 45 resorted to without departing from the spirit of the invention or sacrificing any of its advantages.

What I claim as my invention, and desire to secure by Letters Patent, is—

- 50 1. As a new article of manufacture, a lining composed of a sheet to form one face, a filling material secured to said face at the side edges thereof, tapes or strips extending along said filling material and secured thereto by stitches 55 passing through said tapes or strips, filling material and face, and an imperforate covering composed of a sheet secured over said tapes or strips and filling material to form the opposite face of the same.
- 60 2. As a new article of manufacture, a lining composed of a sheet to form one face, a filling material secured to said face at the side edges

thereof, tapes or strips extending along the filling material and secured thereto by stitches passing through said tapes or strips, filling 65 material and face, and a covering composed of a sheet extending over said tapes or strips and secured to said side edges to form the opposite face of said lining.

3. As a new article of manufacture, a lining 70 composed of a sheet to form one face, a filling material secured to said face at the side edges thereof, tapes or strips extending along the filling material and secured thereto by stitches passing through said tapes or strips, filling 75 material and face, and a covering composed of a sheet extending over said tapes or strips and secured thereto to form the opposite face of said lining.

4. As a new article of manufacture, a lining 80 composed of a sheet to form one face, a filling material secured to said face at the side edges thereof, tapes or strips extending along said filling material and secured thereto by stitches passing through said tapes or strips, filling 85 material and face, and a covering composed of a sheet extending over said tapes or strips and secured thereto and to said side edges to form the opposite face of said lining.

5. As a new article of manufacture, a lining 90 composed of a bottom or back, a filling material secured to said bottom or back at the side edges thereof by stitches, tapes or strips extending along the filling material and secured thereto by stitches, tapes extending 95 along the length of the bottom or back and secured thereto and to the filling material and first-named tapes or strips by stitches, and a covering secured over the stitches in the first-named tapes or strips and side edges by cementing, gluing or pasting the same to said tapes or strips and side edges to form the front or top of the lining.

6. As a new article of manufacture, a lining composed of a bottom or back having turned 105 or bent side edges to form grooves, a filling material secured to said bottom or back and side edges by stitches passing through said bottom or back, grooves and side edges, tapes or strips extending along the filling material, 110 tapes extending along the bottom or back and secured thereto and to said filling material and first-named tapes or strips by stitches, and a covering secured over the stitches in the first-named tapes or strips and side edges 115 by cementing, gluing or pasting the same to said tapes or strips and side edges to form the front or top of the lining.

In testimony whereof I, the said JOHN B. D'HOMERGUE, have hereunto set my hand. 120
JOHN B. D'HOMERGUE.
